PUMP

Charles H. Antrim and Clyde H. Teesdale, Grand Rapids, Mich., assignors to Teesdale Manufacturing Company, Grand Rapids, Mich., a corporation of Michigan

Application May 21, 1937, Serial No. 143,906

9 Claims. (Cl. 103—42)

The present invention relates to pumps and more particularly to gear pumps.

The primary objects of the instant invention are to provide a pump of the type above indicated which is particularly well adapted for feeding oil from a storage tank to the nozzle of an oil burner of an oil burning furnace; to provide such a pump which is suitable for use in conjunction with a storage tank having either a single gravity supply conduit to the furnace or a non-gravity supply conduit to the furnace and a discharge return conduit for returning oil pumped in excess of that required by the burner; to provide such a pump having a diaphragm element associated with the suction conduit for eliminating "pulsation hum"; to provide such a pump whose gear teeth are disposed within laterally disposed marginally overlapping bores of a plate disposed interjacent spaced head plates; to provide such a pump whose pumping mechanism is immersed in the pumped fluid and is thus self-lubricating; to provide such a pump having an improved regulating valve by means of which the amount of oil supplied to the furnace is uniform but whose quantity may be adjusted to varying requirement; and, to provide such a pump which is economical in manufacture, highly efficient in use, and convenient with respect to replacement of worn or defective parts.

An illustrative embodiment of the invention is shown in the accompanying drawings, wherein:

Figure 1 is a front elevational view of a hot air furnace equipped with a motor driven fuel oil burner whose pump draws oil from a fuel oil supply tank through a non-gravity supply conduit and returns oil in excess of burner requirements to the tank through a discharge return conduit;

Figure 2 is an enlarged sectional view of the pump unit per se;

Figure 3 is a sectional view on line 3—3 of Figure 2;

Figure 4 is a sectional view on line 4—4 of Figure 3;

Figure 5 is a sectional view on line 5—5 of Figure 3;

Figure 6 is a sectional view on line 6—6 of Figure 3;

Figure 7 is a sectional view on line 7—7 of Figure 2;

Figure 8 is a sectional view on line 8—8 of Figure 7;

Figure 9 is a sectional view on line 9—9 of Figure 8;

Figure 10 is a diagrammatic view similar to Figure 1 but showing a portion of the pump shown;

in Figure 2 when the same has been modified for use in conjunction with a single gravity feed conduit connected with fuel oil supply tank;

Figure 11 is a plan view on line 11—11 of Figure 2 and showing the diaphragm covered well which eliminates the otherwise audibility of pulsation pump beats;

Figure 12 is a perspective view of some of the several parts of the pump prior to their assembly;

Figure 13 is a fragmentary sectional view of 10 the valve mechanism in one of its operating positions; and

Figure 14 is a fragmentary sectional view of 15 the valve mechanism in another of its operating positions.

Referring then to the drawings wherein like parts of the pump (and the environment in which it is here shown in association) are designated by the same numerals in the several views, a furnace 10, here shown as of the hot air type, has a conventional fuel oil burner 11 mounted on the floor 12 and having its nozzle, not shown, projecting through the ash pit door 13 of the furnace. An electric motor 14, diagrammatically shown in Figure 1, for operating the burner atomizer and 20 the pump 15, through the flexibly and detachably coupled shafts 16, 16' is disposed between the burner 11 and the pump 15.

Fuel oil supplied to the storage tank 17 (in Figure 1, buried outside the building 18 in the 30 ground 19, through the supply conduit 20), is caused to be pumped by the pump 15 from the tank 17 through the intake conduit 21 past the ball check valve 22 and into the core conduit 23 of the cylindrical pump housing 24, through the 35 core conduit 25 of the end plate 26 and its inside screen 27 into the liquid vacuum intake chamber 28 within the pump housing 24, all as best shown by arrows in Figures 1 and 2. The end plate 26 secured to one end of the cylindrical pump housing 24 as by machine screws 29 thus seals one end thereof and its opposite end is sealed by the end plate 30 of the motor 14 as by machine screws 31.

The end plate 30 is provided with a shaft bearing 32 for the shaft 16 and an internal annular 45 flanged web 33 here shown as integrally formed with the cylindrical pump housing 24, dividing the pump housing into the liquid intake chamber 28 and an excess low pressure liquid chamber 34 is likewise provided with a shaft bearing 35 50 for the shaft 16 permitting detachment of the flexibly coupled shafts 16, 16' when it is desired to replace the pump unit by removal of the end plate 26.

The pump 15 here shown as of the gear type,

whose several parts in their unassembled relation are best shown in Figure 12, comprises a pair of spaced head plates 36, 37. A medial plate 38 disposed interjacent these head plates is provided 5 with a pair of laterally spaced marginally overlapping gear retaining bores 39, 40 within which are seated the driving gear 41 keyed to the shaft 16 and the driven gear 42 keyed to a driven shaft 43. The opposite faces of the driving and driven 10 gears are here shown as flush with the opposite inside surfaces of each head plate 36, 37 which head plates and the medial plate 38 are secured together in assembled relation as by the machine screw 44.

15 The head plate 36 is provided with an external annular flange 45 and with a liquid intake port 46, best shown in Figures 8 and 12, affording communication between the liquid intake chamber 28 and the gears 41, 42. The head plate 37 20 is provided with a liquid discharge port 47 in communication with the annular channel 48 communicating with the core conduit 49 leading to the cylindrical valve housing 50 disposed within the excess liquid chamber 34.

25 The web 33 is provided with a laterally disposed annular flange 51 forming a well 52 and the pump 15 in its assembled relation is seated and secured therein by machine screws 53 passing through the external annular flange 45 of the head plate 30 36 and into the flanged wall 51 forming the well 52.

35 Referring now to Figures 3, 4, 5, 6, 13 and 14, the cylindrical valve housing 50 is there shown as an integral portion of the pump housing 24 and a quill 54, whose lower end is sealed by a cap 55 in any suitable manner as by machine screws 56, is disposed within the valve housing 50 within which it is detachably secured by a cap 57, provided with a screw threaded plug 58, as by machine screws 59 passing through the flange 60 40 and into the wall of the housing.

The lower end of this quill is provided with an external annular flute 61 in registration with the core conduit 49 and a transverse bore 62 in 45 registration with the flute 61 provides communication with the interior of the quill. A pair of spaced external annular flutes 63, 64 disposed above the flute 61 respectively register with a pair of spaced internal annular grooves 65, 66 and transverse bores 67, 68 respectively provide 50 communication between the external flute 63 and internal groove 65 and between the external flute 64 and the internal groove 66.

The external flute 63 registers with the elbow 55 core conduit 69 communicating with a flexible discharge conduit 70 leading to the burner 11 and the external flute 64 registers with the core conduit 71 whose orifice 72 communicates with the interior of the excess liquid chamber 34.

60 A piston 73 disposed within the quill 54 has an annular external groove 74 forming a pair of spaced heads 75, 76 and a reduced lower end 77. A longitudinal bore 78 in this piston communicates with a transverse bore 79 thereof communicating with the annular external groove 74. The upper end of the quill 54 is internally screw threaded to receive the screw threaded cap 81 and a coiled expansion spring 82 disposed between the upper end of the piston 73 and the cap 81 70 normally maintains the piston in its position shown in Figure 3.

In instances wherein the oil is drawn from the supply tank 17 through a non-gravity supply conduit 21 and oil in excess of burner requirements is returned to the tank 17 through a dis-

charge return conduit 80 as shown in Figure 1, a threaded plug 83 is inserted into the threaded bore between the core conduit 23 and the parallel core conduit 84 communicating with the excess liquid chamber 34, all as best shown in 5 Figure 2. In instances wherein the oil is fed from the tank 17 to the intake chamber 28 of the pump through the single gravity feed line 85 as shown in Figure 10, the plug 83 is removed and a screw threaded plug 86 is inserted into the 10 threaded bore in which instance excess oil is returned from the excess liquid chamber 34 to the intake chamber 28 through the core conduits 84, 23 as indicated by arrows.

Otherwise audible pulsation pump beats may 15 be eliminated by trapping a pocket of air in a well covered by a diaphragm operable by the pump beats in the intake port or conduit to the pump and as shown in Figures 2 and 11, the well 87 in the end plate 26 is covered by a diaphragm 20 88 secured over its open end by a ring 89 clamping the diaphragm to the annular flanged wall 90 forming the well 87.

Leakage of oil from the excess low pressure liquid chamber 34 between the shaft 16' and its 25 bearing 32 in the end plate 30 is prevented by a sealing element comprising a disc member having an apertured metal hub portion 100 embracing the inner end of the shaft 16' and its flexible portion 101 extending radially therefrom. The 30 opposite marginal borders of the flexible portion 101 of the disc are provided with gaskets 102, 103 and an apertured cupped cap 104, embracing the shaft 16' inwardly of the disc member between which members is provided a coiled expansion 35 spring 105, engages the gasket 103 for securing the marginal edge of the flexible portion 101 of the disc to the end plate 30 as by screws 106.

Operation

In operation, fuel oil within the supply tank 17 is drawn therefrom through the intake conduit 21 (Figure 1) or the intake conduit 85 (Figure 10) in the direction indicated by arrows, through the ball check valve 22, thence through 45 the core conduits 23, 25, past the screen 27 and into the vacuum liquid intake chamber 28 which provides an auxiliary oil supply and within which the pump 15 is immersed.

Oil within the chamber 28 is drawn through 50 the intake or suction port 46 of the head plate 36 of the pump and discharged therefrom through the discharge port 47 of the plate 37, said suction being effected by rotation of the driving gear 41 and its driven gear 42 in the direction indicated 55 by the arrows in Figure 8.

These gears are seated in the laterally spaced marginally overlapping gear retaining bores 39, 40 of the medial plate 38 and since the opposite faces of each gear are flush with the opposite inner surfaces of the head plates 36, 37, oil leakage occurs between the rotating gear teeth and between the opposite surfaces of this medial plate and adjacent inner surfaces of each head plate to lubricate the shaft bearings of the driving shaft 16 and driven shaft 43.

Oil thus discharged through the discharge port 47 passes into the annular groove 48 from where it flows into the core conduit 49, thence into the annular groove 61 of the quill 54 and 70 through the bore 62 thereof into its interior.

Pressure of the pumped oil lifts the piston 73 against the action of the expansion spring 82 from the position of the piston shown in Figure 3 to its position shown in Figure 13 permitting 75

flow of the oil upwardly between the inner wall of the quill and the outer wall of the lower end of the piston, into the annular flute 65 from where it flows through the transverse bore 67 into the 5 elbow core conduit 69 and thence outwardly through the discharge conduit 70 to the nozzle of the burner 11.

Oil pumped in excess of the quantity required by the burner causes the piston to move upwardly against the action of the expansion spring 10 82 from its position shown in Figure 13 to its position shown in Figure 14 permitting flow of the oil through both the bore 67 into the discharge conduit 70 and also upwardly through the 15 hollow piston 73, outwardly through its port 79 and into the bore 68, thence into the conduit 71 from whose orifice 72 the oil flows into the excess low pressure liquid chamber 34.

In instances wherein the oil is drawn from the 20 supply tank 17 through the non-gravity supply conduit 21 and oil in excess of burner requirements is returned to the tank 17 through the discharge return conduit 80 as shown in Figure 1, a threaded plug 83 is inserted into the threaded 25 bore between the core conduit 23 and the parallel core conduit 84 communicating with the excess low pressure liquid chamber 34, all as best shown in Figure 2.

In instances wherein the oil is fed from the 30 tank 17 to the intake chamber 28 of the pump through the single gravity feed line 85 as shown in Figure 10, the plug 83 is removed and a screw threaded plug 86 is inserted into the threaded bore in which instance excess oil is returned from the excess liquid chamber 34 to the intake chamber 28 through the core conduits 84, 23 as indicated by arrows.

Otherwise audible pulsation pump beats are here shown as eliminated by provision of the well 35 87 in the end plate 26 whose open end is covered by the diaphragm 88 secured by the ring 89 clamping it to the annular flanged wall 90 which forms the well 87 within which a pocket of air is trapped.

It will thus be seen that the pump herein shown and described is particularly well adapted for use in supplying fuel oil from a storage tank to the nozzle of an oil burner wherein either a single gravity supply conduit from the tank to the furnace is provided or a non-gravity supply conduit to the furnace and a discharge return line is provided for returning oil pumped in excess of that required by the burner.

The pump is constantly immersed within the liquid providing self-lubrication and otherwise audible "pulsation hum" is eliminated by novel means. The unit herein shown and described is economical in manufacture, highly efficient in use and is obviously convenient with respect to replacement of worn or defective parts and since the chamber 28 is a vacuum chamber and since the chamber 34 is a low pressure chamber sealing of unit is not difficult in production.

While but one specific embodiment of the invention has been herein shown and described, it will be understood that certain details of the construction shown may be altered or omitted without departing from the spirit of this invention as the same is defined by the following 70 claims.

We claim:

1. A unit comprising a sealed housing having its interior divided into a liquid intake chamber provided with a liquid intake port and an excess 75 liquid chamber provided with a liquid discharge

port, a valved housing within the excess liquid chamber having a discharge port for delivering a predetermined quantity of liquid and a by-pass port communicating with the excess liquid chamber for delivering liquid pumped in excess of said predetermined quantity, and a pump within the liquid intake chamber provided with a liquid intake port and having a liquid discharge port communicating with the valved housing.

2. A unit comprising a sealed housing having a 10 division wall dividing it into a liquid intake chamber provided with a liquid intake port and a non-communicating excess liquid chamber provided with a liquid discharge port, a valved housing within the excess liquid chamber having a discharge port for delivering a predetermined quantity of liquid and a by-pass port communicating with the excess liquid chamber for delivering liquid pumped in excess of said predetermined quantity, and a pump within the liquid intake 15 chamber provided with a liquid intake port and having a liquid discharge port communicating with the valved housing.

3. A unit comprising a sealed housing having a partition wall dividing it into a liquid intake 20 chamber provided with a liquid intake port and an excess liquid chamber provided with a liquid discharge port, a valved housing within the excess liquid chamber having a discharge port for delivering a predetermined quantity of liquid and a by-pass port communicating with the excess liquid chamber for delivering liquid pumped in excess of said predetermined quantity, and a pump mounted as a unit within the liquid intake 25 chamber on said partition wall comprising a pair of spaced head plates, a medial plate disposed interjacent the head plates provided with a pair of laterally spaced marginally overlapping gear retaining bores, a driving gear disposed within one bore and a driven gear in mesh with the driving gear disposed within the other bore, one of said head plates having a liquid intake port and the other head plate being provided with a liquid discharge port communicating with the valved housing.

4. A structure comprising a housing divided by a partition wall into a liquid intake chamber and an excess liquid chamber and having a fluid intake port, a fluid discharge port, and an excess fluid discharge port; a quill disposed within the 30 excess liquid chamber and having a fluid intake port extending through the wall of the quill and in registration with the intake port of the housing, a pump located within the liquid intake chamber for causing a flow of fluid under pressure to said quill, a fluid discharge port extending through the wall of the quill and in registration with the discharge port of the housing, and an excess fluid discharge port extending through the 35 wall of the quill and in registration with the excess discharge port of the housing; and a piston slidably mounted within the quill normally sealing the discharge port and excess discharge port but movable under pressure of pumped fluid through the intake port of the quill to provide a predetermined flow of fluid through the discharge port of the quill and to thereafter cause the flow of fluid through the excess discharge port of the quill pumped in excess of said predetermined flow.

5. A unit comprising a sealed housing having a partition wall dividing it into a fluid intake chamber provided with a fluid intake port and an excess fluid chamber provided with a fluid discharge port, a valve housing within the excess

- 3 fluid chamber having a fluid intake port, a fluid discharge port, and an excess fluid discharge port communicating with the excess fluid chamber; a quill disposed within the valve housing having a fluid intake port extending through the wall of the quill and in registration with the intake port of the valve housing, a fluid discharge port extending through the wall of the quill and in registration with the discharge port of the valve housing, and an excess fluid discharge port extending through the wall of the quill and in registration with the excess discharge port of the valve housing; a pump within the fluid intake chamber provided with a fluid intake port and 10 having a fluid discharge port communicating with the intake port of the valve housing; and a piston slidably disposed within the quill normally sealing the discharge port and excess discharge port but movable under pressure of pumped fluid through the intake port of the quill to provide a predetermined flow of fluid through the discharge port of the quill and to thereafter cause the flow of fluid through the excess discharge port of the quill pumped in excess of said 15 predetermined flow.

4 6. A unit comprising a sealed housing having means for dividing it into a vacuum liquid intake chamber provided with a liquid intake port and an excess low pressure liquid chamber 20 provided with a liquid discharge port, a valved housing within the excess liquid chamber having a discharge port for delivering a predetermined quantity of liquid and a by-pass port communicating with the excess liquid chamber for delivering liquid pumped in excess of said predetermined quantity, and a pump within the liquid intake chamber supported by said dividing means and provided with a liquid intake port communicating with said intake chamber and having a liquid discharge port communicating with the valved 25 housing.

5 7. A unit comprising a sealed housing having a partition dividing the housing into a vacuum fluid intake chamber provided with a fluid intake port and an excess low pressure fluid chamber provided with a fluid discharge port, a valve housing within the excess fluid chamber having a fluid intake port communicating with said fluid intake chamber, a fluid discharge port, and an excess fluid discharge port communicating with the excess fluid chamber; a quill disposed within the valve housing having a fluid intake port extending through the wall of the quill and in registration with the intake port of the valve housing, a fluid discharge port extending through the wall of the quill and in registration with the discharge port of the valve housing, and an excess fluid discharge port extending through the wall of the quill and in registration with the excess discharge port of the valve housing; a pump within the fluid intake chamber provided with a fluid intake port and having a fluid discharge port communicating with the intake port of the valve housing; and a piston slidably disposed within the quill normally sealing the discharge port and excess discharge port but movable under pressure of pumped fluid through the intake port of the quill to provide a predetermined flow of fluid through the discharge port of the quill and to thereafter cause the flow of fluid through the excess discharge port of the quill pumped in excess of said predetermined flow.

6 8. A unit comprising a sealed housing having a partition dividing it into a liquid intake chamber and an excess liquid chamber and having an annular flange forming a well in the liquid intake chamber, said housing being provided with a liquid intake port and a liquid discharge port, a valved housing located within the excess liquid chamber and formed integral with one of the walls of the sealed housing and having a by-pass communicating with the excess liquid chamber, and a pump mounted as a unit within said well and removable therefrom as a unit and having means for detachably securing it to said annular flange.

7 9. A unit comprising a sealed housing having a partition dividing it into a liquid intake chamber and an excess liquid chamber and having an annular flange forming a well in the liquid intake chamber, said housing being provided with a liquid intake port and a liquid discharge port, a valved housing located within the excess liquid chamber and formed integral with one of the walls of the sealed housing and having a by-pass communicating with the excess liquid chamber, and a pump mounted as a unit within said well and removable therefrom as a unit and comprising inner and outer head plates, a medial plate disposed interjacent the head plates and provided with a pair of laterally spaced marginally overlapping gear retaining bores, a driving gear disposed within one bore, a driven gear disposed within the other bore in mesh with the driving gear, said gears having their faces substantially flush with the faces of the medial plate, one of said head plates having a liquid intake port and the other head plate being provided with a liquid discharge port, fastening means for securing said plates together for enabling the pump to be placed in and removed from said well as a unit, and separate fastening means for securing the outer head plate to the annular flange.
